UNITED STATES PATENT OFFICE.

GALE B. DE WITT, OF COMANCHE, OKLAHOMA.

PNEUMATIC WELL.

Application filed January 3, 1927. Serial No. 158,662.

This invention relates to an improved pneumatic well wherein a column of air under pressure is ejected into the well casing for elevating the fluid through the tubing.

5 The novelty of the improvement resides in the provision of novel air actuated means for elevating the fluid through the tubing at desired intervals of time.

Briefly, the invention has reference to a 10 structure which includes, among other parts, a casing having an enlarged housing located between the lower end of the casing and the perforated anchor at the bottom of the equipment, there being upper and lower partition members located in this housing to 15 form a fluid receiving chamber. In this chamber is a float slidably mounted upon the valve end of the tubing which depends into the chamber. The float is moved down- 20 wardly by air pressure injected into the casing, in order to force the fluid from the chamber through intake ports in the tubing.

One feature of construction is the lower 25 partition member formed at the bottom of the housing, the same being in itself, made up of upper and lower walls of somewhat conical form, and there being a central guide formed in which a fluid valve seat and carrier is located.

30 Another feature of construction is the valved tubing which serves as a conveyor for the fluid being elevated and which has its lower end slidably mounted in the guide in said partition member in a manner to control the fluid valve.

35 Other features and advantages of the invention will become apparent from the following description and drawing.

In the accompanying drawing forming a 40 part of this application and in which like numerals are employed to designate like parts throughout the same:

Figure 1 is a longitudinal section through a structure constructed in accordance with 45 the present invention.

Figures 2 and 3 are horizontal sections taken approximately upon the plane of lines 2-2 and 3-3, respectively, of Figure 1.

Referring now to the drawing in detail, 50 it will be seen that the lowermost section of the casing is designated by the reference character 1. This is preferably connected with the part 2 which is, for convenience, referred to as the housing. This housing is 55 actually made up of a central cylinder 3, and upper and lower reducing sections 4 and 5,

respectively. The section 5 is pivotally connected to the customary apertured anchor 6. All the parts are connected together by coupling rings 7. The fluid elevating tubing 60 is generally designated by the reference character 8, and this, of course, extends down into the casing and housing in spaced relation as represented. Before considering the specific construction of the tubing I wish 65 to direct attention to the fact that the aforesaid fluid receiving chamber is designated generally by the reference character 9, and this is formed by the presence of a partition plate 10 clamped between the parts 3 70 and 4, and provided with apertures; together with a lower partition or closure member 11. The latter is formed integral with the bottom of the cylinder or part 3. It comprises a lower cone 12 of imperforate form, a 75 smaller upper cone 13 and a flange 14 having apertures 15 formed adjacent its periphery. These cones are connected by a neck 16 provided with fluid ports 17. The upper portion 80 of the neck which operates as a guide, is smooth, and the lower portion is internally screw threaded. Tapped into this screw threaded portion is a valve mounting and carrier 18, the upper end of which is formed into a valve seat, the lower end of 85 which is provided with fluid intake ports 19. The valve is represented at 20 and rests upon the seat and includes a stem 21 extending down through an opening in the bottom of the carrier 18. A spring surrounds this stem 90 and serves to normally unseat or open the valve in order to uncover ports 17. An annular float of suitable material 22 is located for sliding movement in the chamber.

The tubing includes a pipe section 23 carrying a spider 24. This spider has a central depending valve stop with which the ball check valve 25 cooperates. The ball check valve is seated upon the valve seat formed at the upper end of the fitting 26. Connected to this fitting is a pipe section 27 closed at its lower end but formed intermediate its end with a multiplicity of fluid intake ports. Slidably mounted on the lower end portion of this pipe section is a float stop washer 28 held up by a coiled spring 29. The coiled spring engages the shoulder 30, this shoulder is formed on a collar which is threaded onto the lower end of the pipe section 27, and the pipe section and collar are formed with registering openings as shown.

In the operation of this device the weight

of the tubing is employed for closing the valve 20. This valve is normally unseated. It follows also that the tubing is consequently elevated by suitable means, and held in an elevated position to allow the spring to unseat the valve 20. This valve 20 is slidably mounted in the guide formed by the neck 16. The lower end of the tubing is adapted to slide down into this neck to engage the valve. Assuming now that the valve 20 is unseated, and the tubing elevated, it is obvious that the fluid will enter through the anchor 6 and flow upwardly through the port 19, 17 and 15 into the receiving chamber 9. The chamber will consequently become filled in due time. Now, the air under pressure is fed downwardly through the casing and it passes through the holes in the partition 10. In so doing it forces the float 22 downwardly in the chamber, displacing the fluid from the chamber through the intake port in the tubing. It is thereby elevated in the tube, unseating the valve 25 and rising upwardly in a well known manner. Before the air is turned on, the tubing was of course lowered so that its weight was brought to bear upon the valve 20 in order to close the valve 20. In the course of its downward movement the float comes into contact with the washer and forces the washer down against the pressure of the coil spring 29. The downward movement of the washer and float continues until the washer rests on top of the part 13, the float being at this level permits the compressed air to pass through the perforations on the tubing, forcing all of the fluid from the tubing. Obviously, when the tubing is again lifted and the valve 20 opened, the fluid repeats the operation of entering the chamber, and elevating the float 22 to the position shown in the drawing.

When the air, under pressure is fed downwardly through the casing it passes through the holes in the partition 10. In so doing it forces the float 22 downwardly in the chamber. The purpose claimed for this float is that it assists the fluid to retain its surface tension and permits the fluid in the chamber or central cylinder 3 to pass through the intake ports in the tubing without breaking up the solid body of fluid with air or gas pockets, which would occur if the air pressure would strike an unprotected fluid surface.

When the float 22 engages the disk 28, compressing the spring 29, no value or good is claimed directly toward the removal of the fluid. However, when action of removal of fluid from the well has been completed and pressure from central cylinder 3 removed, the spring assists materially in assisting incoming fluid into the cylinder 3 to raise float.

A certain amount of foreign substance is always found in deep wells. This substance or grit would naturally collect in the bottom

of the cylinder 3. If we did not provide a spring 29, it is possible that the float would get stuck in bottom of cylinder 3. The disk or washer 28 is simply a convenient part on which the float might rest as it comes in contact with the spring 29. 70

It is believed that persons skilled in the art to which the invention relates will be able to obtain a clear understanding of the construction and operation of the invention 75 from the foregoing description considered in connection with the drawing. In view of this, a more lengthy description is thought unnecessary.

Minor changes coming within the field of 80 invention claimed may be resorted to if desired.

Having thus described the invention, what I claim is:—

1. In a well structure of the class described, a well casing including a housing provided with a valved fluid receiving chamber, an air pressure operated float mounted in said chamber, and valved tubing disposed within the casing and depending into the 90 housing and mounted for controlling the valve in said chamber. 85

2. In a well structure of the class described, a well casing, an apertured anchor, and an enlarged housing interposed between 95 and connected with the casing and anchor, upper and lower partition members located in said housing and formulating a fluid receiving chamber, a spring opened valve operable with the lower partition member, said last named partition member being provided with a guide and fluid passages, and a valved fluid conducting tube structure depending through the casing and into the housing and having its lower end slidably mounted in said guide in a position to rest upon 100 said valve for closing the latter against the tension of its spring, together with a float 105 slidably mounted in said chamber and surrounding said tube. 110

3. In a well structure of the class described, a well casing, an apertured anchor, a housing interposed between and connected with the casing and anchor, upper and lower vertically spaced partition members mounted in said housing and forming a fluid receiving chamber therebetween, the upper partition member being formed with air ports, the lower member embodying vertically spaced upper and lower parts connected together at their central portions by a cylindrical neck, said neck functioning additionally as a guide, a valve carrier fitted into said neck and provided with a valve seat and fluid intake ports, a spring opened valve mounted upon the carrier and cooperable with said seat, said neck and upper part of the partition member being provided with cooperating fluid ports, said upper partition member being formed with a guide opening 125 130

in alignment with said guide, and valved tubing depending through said casing and into said chamber and having its lower end closed and resting upon said valve for holding the valve down upon its seat, the tubing being provided with fluid intake ports disposed within the area of said chamber.

4. In a well structure of the class described, a well casing, an apertured anchor, an enlarged housing interposed between the lower end of the casing and anchor and connected respectively with the casing and anchor, said housing being of cylindrical cross section, upper and lower partition members located in the housing and forming a fluid receiving chamber therebetween, the upper partition member being formed with air holes and a central guide opening, the lower partition member being provided with fluid

intake ports and a central guide, a spring 20 opened valve carried by the lower partition member for controlling the entrance of fluid into said chamber, and fluid conducting and elevating tubing depending through said casing and into said chamber, a check valve located in the lower portion of the tubing, said lower portion including a pipe section closed at its bottom and having said closed bottom extending into the guide in said lower partition member and adapted to rest upon said spring opened valve for closing said valve, said lower section being provided with fluid intake ports, a spring pressed washer 30 slidable on said pipe section, and an annular float located in said chamber and also slid- 35 able upon said lower section.

In testimony whereof I affix my signature.
GALE B. DE WITT.
